UNITED STATES PATENT OFFICE.

CLARKSON A. DISBROW, OF NEW ROCHELLE, NEW YORK, ASSIGNOR TO THE RAIL JOINT COMPANY, OF NEW YORK, N. Y., A CORPORATION OF NEW YORK.

TRACK LINER.

Application filed May 1, 1923. Serial No. 636,033.

This invention relates to a novel track lining device and has for its principal object the provision of a simple and economical tool which will meet practical requirements with a minimum amount of labor.

Another object is to provide a rail bearing lever for shifting the rail laterally which is of such a character that any tendency to elevate the rail during the shifting action will be reduced to a minimum.

A further object is to provide the tool with efficient anchoring means whereby the tool may be readily positioned under a rail, even when the ballast closely approaches the rail, and the tool secured by the anchoring means against movement during the rail shifting operation.

A still further object lies in the provision of a track lining device in which means are provided for readily positioning the operating lever in its initial position when the tool is being employed on a track which is substantially filled with ballast.

With the above and other objects in view which will more readily appear as the nature of the invention is better understood the same consists of the novel construction, combination and arrangement of parts herein-after more fully described, illustrated and claimed.

A preferred and practical embodiment of the invention is shown in the accompanying drawings, in which:

Figure 1 is a sectional view of a railroad track showing in side elevation, one form of my improved track lining device.

Figure 2 is a detail sectional view of one end portion of the anchor showing more clearly the detachable anchoring cleat.

Figure 3 is a bottom plan view of the construction shown in Fig. 2, on line 3-3 of Fig. 2.

Figure 4 is a sectional view taken on the line 4-4 of Fig. 2, and showing the anchoring element in elevation.

Similar reference characters designate corresponding parts throughout the several figures of the drawings.

The present invention particularly is directed to certain improvements in track liner construction intended better to meet track requirements and practical conditions, especially as to proper emplacement and anchoring of the track liner base on the ballast

and the mounting and formation of the rail engaging lever in such a way as to leave a minimum projection between the base of the liner and the base of the rail; and to also facilitate the movement of the rail engaging lever with the pivot of the latter relatively close to the rail base and at the same time permitting the lever to move the track laterally with a minimum or negligible lifting force.

A practical embodiment of the invention is shown in the accompanying drawings and referring now to Figures 1 and 2 the device therein shown comprises the base A, rail-bearing lever B, and an operating lever C. The base A may be formed of a flat elongated plate having strengthening ribs 1-1 which extend downwardly along its longitudinal edges. The base, adjacent the inner end thereof, is formed with spaced depending ears 3-3, and between said ears with an opening 4. Formed upon the upper side of the base is a longitudinal series of bearing shoulders 5.

The rail-bearing lever B is pivoted at its inner end to the ears 3-3 by a pin 6, the lever extending through the opening 4. This lever is of angular formation, that is, one end is provided with offset toe or thrust portion T having an oblique cam face and an operating portion 8, the said cam face being disposed at an angle of approximately 45° relative to the plane of the base when the lever is in its initial position. This lever construction is very important in that it permits the pivot 6 of the lever to be positioned more directly under the rail R than would be otherwise possible. This position of the pivot 6 together with the angular toe thrust portion T, will insure a lateral movement of the rail R upon actuation of the operating lever C, with a minimum amount of lifting action on said rail. Furthermore, the pivot 6 being thus positioned as close as possible to the point of work, the rail will be shifted laterally with a minimum effort.

The operating lever C includes a cam 9 which is adapted to be successively fulcrumed at one end of its arc on the bearing shoulders 5 of the base A, and have sliding contact with the underface of the operating portion 8 of the rail-bearing lever B, said under face being formed with a guiding channel 10 which receives the contacting

portion of the cam 9 and serves to prevent relative lateral movements between the parts.

The value of a track lining device depends, to some extent, upon the rapidity with which it can be positioned on the track in readiness for use. Frequently, the track is filled with ballast so that it is necessary to remove some of the ballast in order to place 10 the track lining device in operative position, because of the space required under the rail for the anchoring means of the base. It is therefore advisable under these conditions, to employ a device having removable 15 anchoring means. To this end I provide as shown in Figs. 2, 3 and 4, a device including a base A and a rail-bearing lever B pivoted thereto, the base being formed adjacent its inner end with a vertical opening 15 of a 20 shape to fit a removable cleat or anchoring means F. This cleat is formed of metal and includes a central portion 16 and outwardly extending flanges 17—17, thus forming a wide pocket for receiving ballast. 25 The upper end of the anchor is formed with a tapping head 18, and this head is formed with a transverse opening 19. The lower end of the anchor is beveled to form a plurality of points or wedges 20—20 for facilitating the entrance of the anchor in the ballast, when driven downwardly under impact of a hammer or other tool on the head 18. When applying this form of my device, 30 the anchor F is removed, and the inner end 35 of the device is positioned under the rail. The anchor F is then inserted into the opening 15 and driven into the ballast. After

the track has been thrown, that is, shifted laterally, the anchor F can be readily removed by applying a tool to the opening 19 40 thereof, and the device can then be changed to a new position.

Without further description, it is thought that the features and advantages of the improvement will be readily apparent to those skilled in the art, and it will of course be understood that changes in the form, proportion and minor details of construction may be resorted to without departing from the spirit of the invention or the scope of 50 the appended claims.

I claim:—

1. A track lining device including a base provided at one end portion thereof with an opening, means carried by said base at 55 the upper side thereof and in rear of the said opening for exerting a lateral force against the rail, and an anchoring plate removably mounted in the said opening and of a cross-sectionally flanged formation, the said plate being provided with a pointed lower end for penetrating the ballast and at its upper end with a tapping head engaging over the said base.

2. A track lining device including a base, 60 means carried by the base for exerting lateral force against the rail, and removable anchoring means carried by the base, said anchoring means comprising a central portion and outwardly extending flanges 70 conjointly forming a ballast-receiving pocket.

In testimony whereof I hereunto affix my signature.

CLARKSON A. DISBROW.
